UNITED STATES PATENT OFFICE.

WILLIAM P. DEVINE, OF DORCHESTER, MASSACHUSETTS, ASSIGNOR TO FARRINGTON MANUFACTURING COMPANY, OF ROXBURY, MASSACHUSETTS, A CORPORATION OF MAINE.

MACHINE FOR APPLYING COVERING MATERIAL TO ARTICLES.

1,289,696.

Specification of Letters Patent. Patented Dec. 31, 1918.

Application filed August 2, 1918. Serial No. 247,985.

To all whom it may concern:

Be it known that I, WILLIAM P. DEVINE, a citizen of the United States, residing at Dorchester, county of Suffolk, State of Massachusetts, have invented an Improvement in Machines for Applying Covering Material to Articles, of which the following description, in connection with the accompanying drawing, is a specification, like characters on the drawing representing like parts.

This invention relates to machines for applying covering material such as leather, textile material and materials of a similar character to articles such, for example, as eye-glass cases, which machines may be of the general type disclosed in the patent to Brown No. 1,117,162 granted November 17, 1914.

The object of the invention is to provide for the operation of the wipers with which such machines are provided in such a manner that ready access may be had by the operator to the space between the coöperating dies.

A further object of the invention is to provide a rotary actuator in the bed plate for the wipers of the machine together with operative connections between the said actuator and wipers whereby the proper protecting and retracting movement of the wipers is effected by the rotary movement of the actuator and in which preferably the projecting rotary movement of the actuator is effected by a plunger projecting from the die coöperating with the die in the wiper bed plate.

These and other objects and features of the invention will more fully appear from the accompanying description and drawings and will be defined by the claims.

While the invention is not to be restricted to any particular form of machine in its broader aspects it is for the purpose of illustrating the invention disclosed herein in connection with a machine for applying covering material to eye-glass cases and more particularly to the cover of such cases. The shape of the article to be covered, the shape of the necessary dies, the particular means for effecting the relative movement of the dies, the number of wipers employed,

the timing of the movement of the wipers, and various other features of the machine are not however specifically involved in the 55 invention and may obviously be varied as desired to embody the invention subject to the requirements of the claims.

In the drawings,

Figure 1 is a view in central vertical cross 60 section of a portion of the machine;

Fig. 2 is a top plan view of the bed plate and receiving die;

Fig. 3 is a bottom plan view of the die carried and coöperating dies; 65

Fig. 4 is a view partly in vertical section taken transversely through the center of the dies;

Fig. 5 is a view similar to Fig. 2 on an enlarged scale showing the cover plate of 70 the bed plate removed, an eye-glass case in position, and the wipers in projected position;

Fig. 6 is a detail in vertical cross section taken on the line A—A of Fig. 5 showing 75 the relation of the dies and article being covered with a wiper in projected position;

Fig. 7 is a detail in vertical cross section taken on the line B—B of Fig. 5 through the actuator showing the spring for moving 80 the actuator in one direction;

Fig. 8 is a detail in vertical cross section taken on the line C—C of Fig. 5 showing the operative connection between the plunger and actuator; 85

Fig. 9 is a side elevation of the entire machine with the dies in closed position;

Fig. 10 is a top plan view of the bed plate with the cover removed and showing a modified form of connection between the plunger and actuator to permit sequential movement of the wipers. 90

The machine illustrated for the purpose of disclosing a preferred form of the invention is particularly designed for applying 95 covering material to the cover portion of eye-glass cases but is obviously readily adaptable to applying covering material to various other articles. It comprises a supporting frame 1 which may be secured to a table or other support 2 by bolts 3 and which is provided with a horizontally projecting arm 4 and an overhanging arm 5. The horizontal arm 4 supports a bed plate 6

ering material and clamping it against the edge of the article such as the eye-glass case. The parts are then in the position substantially as shown in Fig. 4 and the covering material is firmly clamped and pressed against the article on the bottom surface and at the inturned edges. The handle lever is then elevated; the article removed and the operation repeated.

10 The wipers may be of any number and have their effective edges shaped to correspond with the edge of the article to be covered. These wipers may be of various construction but are herein shown as consisting of generally flat plates 11, 12, 13 and 14 sliding in the general radial direction in ways 44, 45, 46 and 47 respectively cut in the bed plate 6 and held in place by the cover plate 15. The wipers are given their projecting and retracting movements by an actuator 15 rotatably mounted in the bed plate and which in the preferred form illustrated consists of a metal ring sector 48 rotatably mounted in an annular way 49 cut in the bed plate 6 concentric with its center. This rotary actuator 48 is operatively connected to the several wipers to secure the proper movements thereof either simultaneously or sequentially. For this purpose pin and cam slot connections are conveniently used and in the form shown the actuator is provided with upwardly projecting pins 50, 51, 52 and 53 entering the cam slots 54, 55, 56 and 57 respectively. In Fig. 5 the actuator is shown as having been moved to bring the pins to the outer end of the cam slots and thus to have projected the wipers to their extreme inner position turning the edge of the covering material upon the article.

20 When the actuator is moved in the opposite direction the wipers are simultaneously retracted. If the action of the wipers is to be a sequential one then a construction such as shown in Fig. 10 may be employed wherein the cam slots in the wipers are provided with concentric sections 58, 59, 60 and 61 respectively. These may be arranged to give the required sequence of action and in the construction shown are so arranged that the wipers 62 and 63 are first projected and then the wipers 64 and 65 are subsequently projected, the retracting movements taking place in inverse order.

25 Thus in either case upon rotation of the actuator in one direction projecting movement of the wipers is effected and upon rotation of the actuator in the opposite direction retraction of the wipers is effected.

30 The rotary movement of the actuator to effect the projection of the wipers is preferably secured by means movable with respect to the actuator and preferably by a means connected with the vertically movable die carrier while the rotary movement of the actuator to effect the retraction of the wipers

is preferably secured by a spring. A preferred construction for thus effecting the rotary movements of the actuator is illustrated.

The rotary actuator as has been noted is 70 preferably a ring shaped sector 48. At one end of the sector the actuator is cored out and in the core is mounted a spring 66 and preferably a plunger 67. This spring acts through the plunger against an abutment 75 68 secured rigidly in place in the way 49 by a set screw 69. The spring thus interposed between the bed plate and the actuator normally acts to effect the rotary movement of the actuator which causes the retracting 80 movement of the wipers. The rotary movement of the actuator which causes the projecting movement of the wipers is shown as secured by a plunger 70 depending from the vertical movable die carrier 8 and vertically 85 adjustable therein by means of the nuts 71 on its screw threaded shank. This plunger carries a projecting cam 72 with an inclined lower face and the lower end of the plunger is steadied by riding into an aperture 73 in 90 the bed plate. The adjacent end of the ring-shaped sector constituting the rotary actuator 48 is provided with an opposed cam member 74 having an inclined upper face and this cam member 74 is preferably pivotally mounted at 95 in the actuator so as to swing upwardly. It will thus be seen that as the die carrier descends the plunger 70 enters the aperture 73 and its cam 72 comes into contact with the cam 74 of the rotary 100 actuator. The result is that the rotary actuator is cammed around in its way in opposition to the spring 66 and through the pin and slot connections acts to give the proper projecting movements to the wipers. 105 The cam 72 of the plunger passes beneath the cam 74 and as the rotary actuator moves in the retracting direction before the dies separate the pivoting of the cam 74 enables the plunger to recede and in its receding movement swing the cam 74 upwardly. The cam 74 is normally brought to its operative position by gravity or if required a spring 110 76 may assist in returning it to normal position.

115 It will thus be seen that this invention provides for an entirely free space or opening between the coöperating dies so that the operative may readily place the article to be covered in position and remove it when covered from between the dies. The plunger 70 is conveniently located at the rear or away from the operative as shown in the drawings leaving the entire space between the dies unobstructed. It will also be seen that the 120 mechanism is of a simple construction, that the parts may readily be made strong and durable and subject to a minimum amount of wear, and that the operation of projecting and retracting the wipers is effectively. 125 130

and accurately controlled. All the parts are readily accessible for removal or repair when necessary.

Having fully described my invention, what I claim as new and desire to secure by Letters Patent is:

1. A machine for applying covering material comprising a bed plate, a die in said bed plate to receive the article and covering material, a plurality of wipers mounted in said bed plate to be projected toward and retracted from said die and acting when projected to fold the edge of the covering material over the edge of the article, an actuator rotatably mounted in said bed plate, operative connections between said actuator and wipers whereby the projecting movement of the wipers will be effected upon rotation of the actuator in one direction and retracting movement upon rotation in the opposite direction, and means movable with respect to said actuator to effect the rotary projecting movement thereof.
2. A machine for applying covering material comprising a bed plate, a die in said bed plate to receive the article and covering material, a plurality of wipers mounted in said bed plate to be projected toward and retracted from said die and acting when projected to fold the edge of the covering material over the edge of the article, an actuator rotatably mounted in said bed plate, operative connections between said actuator and wipers whereby the projecting movement of the wipers will be effected upon rotation of the actuator in one direction and retracting movement upon rotation in the opposite direction, and a spring interposed between said bed plate and actuator and acting to effect the rotary retracting movement of the actuator.
3. A machine for applying covering material comprising a bed plate, a die in said bed plate to receive the article and covering material, a plurality of wipers mounted in said bed plate to be projected toward and retracted from said die and acting when projected to fold the edge of the covering material over the edge of the article, an actuator rotatably mounted in said bed plate, operative connections between said actuator and wipers whereby the projecting movement of the wipers will be effected upon rotation of the actuator in one direction and retracting movement upon rotation in the opposite direction, a spring interposed between said bed plate and actuator and acting to effect the rotary retracting movement of the actuator, and means movable with respect to said actuator to effect the rotary projecting movement thereof.
4. A machine for applying covering material comprising a bed plate, a die in said bed plate to receive the article and covering material, a plurality of wipers mounted in

said bed plate to be projected toward and retracted from said die and acting when projected to fold the edge of the covering material over the edge of the article, an actuator rotatably mounted in said bed plate, operative connections between said actuator and wipers whereby the projecting movement of the wipers will be effected upon rotation of the actuator in one direction and retracting movement upon rotation in the opposite direction, a plunger movable with respect to the bed plate, and means acting upon the movement of the plunger in one direction to effect the rotary projecting movement of the actuator.

5. A machine for applying covering material comprising the construction defined in claim 4 together with a spring interposed between said bed plate and actuator and acting to effect the rotary retracting movement of the actuator.

6. A machine for applying covering material comprising a bed plate, a die in said bed plate to receive the article and covering material, a plurality of wipers mounted in said bed plate to be projected toward and retracted from said die and acting when projected to fold the edge of the covering material over the edge of the article, an actuator rotatably mounted in said bed plate, operative connections between said actuator and wipers whereby the projecting movement of the wipers will be effected upon rotation of the actuator in one direction and retracting movement upon rotation in the opposite direction, a plunger movable with respect to the bed plate, and coöperating cams upon said plunger and actuator acting to effect the projecting movement of the actuator upon the movement of the plunger in one direction and yielding with respect to each other to permit the reverse movement of the plunger.

7. A machine for applying covering material comprising a bed plate, a die in said bed plate to receive the article and covering material, a plurality of wipers mounted in said bed plate to be projected toward and retracted from said die and acting when projected to fold the edge of the covering material over the edge of the article, an actuator rotatably mounted in said bed plate, a pin and cam slot connection between each wiper and the actuator whereby the projecting movement of the wipers will be effected upon rotation of the actuator in one direction and retracting movement upon rotation in the opposite direction.

8. A machine for applying covering material comprising the construction defined in claim 7 together with the spring interposed between said bed plate and actuator and acting to effect the rotary retracting movement of the actuator.

9. A machine for applying covering mate-

rial comprising the construction defined in claim 7 in which one or more of the said cam slots are provided with sections concentric to the axis of rotation of the actuator 5 whereby the said wipers may have a predetermined sequential movement.

10. A machine for applying covering material comprising a bed plate, a die in said bed plate to receive the article and covering material, a plurality of wipers mounted in said bed plate to be projected toward and retracted from said die and acting when projected to fold the edge of the covering material over the edge of the article, a ring-shaped actuator rotatably mounted in said bed plate, a pin and cam slot connection between each wiper and the ring-shaped actuator whereby the projecting movement of the wipers will be effected upon rotation of the actuator in one direction and retracting movement upon rotation in the opposite direction.

11. A machine for applying covering material comprising the construction defined in claim 10 together with a spring interposed between said bed plate and ring-shaped actuator and acting to effect the rotary retracting movement of the actuator.

12. A machine for applying covering material comprising a bed plate, a die in said bed plate to receive the article and covering material, a die carrier and coöperating die movable relatively to said receiving die to assist in applying the covering material, 35 means for effecting the relative coöperating

movement of said die carrier and bed plate, a plurality of wipers mounted in said bed plate to be projected toward and retracted from said receiving die and acting when projected to fold the edge of the covering material over the edge of the article, an actuator rotatably mounted in said bed plate, operative connections between said actuator and wipers whereby the projecting movement of the wipers will be effected upon rotation of the actuator in one direction and retracting movement upon rotation in the opposite direction, a plunger projecting from the die carrier toward the bed plate and operative means between the plunger and actuator 45 acting to effect the rotary projecting movement of the actuator upon the movement of the die carrier toward the bed plate.

13. A machine for applying covering material comprising the construction defined in claim 12 in which the operative connections between the said plunger and actuator consists of a pair of coöperating cams one of which yields to permit the separating movement of the die carrier and bed plate. 60

14. A machine for applying covering material comprising the construction defined in claim 4 together with means for adjusting the plunger with respect to the die carrier thereby to vary the projecting movement of the wipers.

In testimony whereof, I have signed my name to this specification.

WILLIAM P. DEVINE.
